(57) CLAIM

The ornamental design for a grill, as shown and described.

DESCRIPTION

FIG. 1 is a front side perspective view of our grill;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a front side perspective view of a second embodiment thereof;

FIG. 8 is a front elevation view of FIG. 7;

FIG. 9 is a rear elevation view of FIG. 7;

FIG. 10 is a left side elevation view of FIG. 7;

FIG. 11 is a right side elevation view of FIG. 7; and,

FIG. 12 is a top plan view of FIG. 7.

The broken line showing is for illustrative purposes only and forms no part of the claimed design.
